HYDRAULIC AIR COMPRESSOR

George W. Harris and John Voss, Chicago, Ill.

Application December 20, 1937, Serial No. 180,756

15 Claims. (Cl. 261—76)

This invention concerns fluid compression devices, and more particularly a form of hydraulic compressor adapted to operate from the city water mains.

5 One of the important objects of the invention is the provision of a hydraulic air compressor adapted to operate from the city water mains and operable to compress air for general use and especially for use with beverage dispensing apparatus.

Another object is the provision of a hydraulic air compressor which can be operated from the city water mains and which is adapted to wash as well as compress air.

15 Another object is the provision of a simple and relatively inexpensive air compressing device especially suitable for use with beverage dispensing apparatus and which may be readily connected with the local hydrant for operation by water under pressure from the city mains.

20 Still another object is the provision of a fluid compression device including a tank and an injector for delivering water under pressure into said tank and also operable to draw air into the 25 tank, together with float-operated valve means and check valve means so arranged that as the water level rises in the tank the inducted air becomes increasingly compressed and escapes under pressure into a storage tank while the float 30 means operates certain valves to release the water from the tank so that the cycle of injection and compression may be repeated.

Other objects and novel aspects of the invention reside in certain details of construction and 35 operation especially with respect to the injection valve, the check valve arrangement and the quick acting float control valve mechanism, all of which will appear as the following description proceeds in view of the drawing, in which:

40 Fig. 1 is a vertical cross section through the compressor unit; while

Fig. 2 is an enlarged top plan detail of a valve catch means.

The present invention contributes certain improvements over the hydraulic compression device for use with beer apparatus shown in United States Patent No. 2,007,488 to John Voss, and in one of its preferred embodiments the present invention includes a tank 10 having a removable 45 head 11 secured to the main tank portion by means such as the nuts and bolts 12 engaged in flange portions 13 on the head and main tank portions. A suitable form of gasket 14 is provided between the flange portions 13 to complete the air seal. The bottom 15 of the tank 50

is concave and has a depending discharge conduit 16 at its lowermost central portion and through which water forced into the tank is permitted to escape under certain conditions.

5 Threaded into a nipple 17 in the head 11 is an injector unit generally indicated at 18 and including a main conduit portion 19 adapted for connection with the city water supply and leading to the bottom of the tank through a stand pipe 20 open at its lower end 21 just above the 10 concave bottom wall. An extension 22 on the injector 18 provides an air inlet 23 leading past a light weight valve 24 having its stem 25 slidably seated in a plug 26 threaded into the extension 22. A passage 27 communicates at an 15 angle from the valve 24 into the conduit portion 19 at a point just above the juncture 28 of a small-diameter water feed tube 29 and a larger-diameter injector tube 30 disposed in the conduit portion 19, the arrangement being such that as 20 the water passes under pressure down through the smaller-diameter tube 29 and by its own velocity and momentum on into the larger tube 30, air is dragged through the conduit portion 21 in around the juncture 28 between the larger and 25 smaller tubes. It will be observed that the stand pipe 20 is of considerably larger diameter than the injection tube 30 to obviate any undue back pressure. There is also a smaller valve operating 30 duct 27.

As the water level rises, the air-tight float 31 within the tank rides upwardly on a vertical guide rod 32 attached at its lower end by pin means 33 to a plug or stopper 34 which normally seats in or closes the discharge duct 16, the upper end 35 of the rod 32 terminating in a tapered nose portion 35 which projects in the central opening 36 of a toroidal spring ring 37 (see Fig. 2) seated in a chamber 38 in the bottom of a compression valve structure 39 threaded into a nipple portion 40 in the top of the tank. The chambered portion 38 is closed by a plate 41.

45 It will be observed that the guide rod 32 may shift up and down along a vertical line to open and close the discharge or drain opening 16. When the rod 32 moves upwardly, the tapered nose portion 35 wedges into the toroidal spring latch 37 until a circumferentially curved portion 42 is gripped by the spring to hold the rod 32 50 in raised position with the drain 16 open. In this latter position the nose portion 35 acts also as a stop valve by virtue of the fact that it seats in a reduced air discharge passage 43 in the structure 39 and thus closes off the discharge or compression line from the interior of the tank. 55

When the guide rod 32 is in its lowered position, as seen in Fig. 1, with the drain 16 closed, the rising column of water within the tank compresses the inducted air which escapes around the nose portion 35 of the guide rod and past a rubber lip valve 44 into an enlarged float chamber 45 and around a normally open float valve 46 and past another normally closed rubber lip valve 47 into the reservoir or compression tank.

The float valve 46 may be of any commonly known type which includes a float 48 connected by a guided arm 49 to the valve and operable when any liquid or water accidentally gets past the lower valves and escapes from the tank into the chamber 45. When the compressor is used for beverage dispensing purposes, it is necessary to guard against any possibility of water reaching the main compression line, and the float valve structure 46-49-48 serves this end.

As the water column rises within the tank, back pressure in the air induction line will permit the easy operating valve 24 to close, the air previously inducted meanwhile being continuously compressed until the float 31 reaches a predetermined level to terminate the compression phase of the operation. The closed sleeve portion 31' of the float 31 terminates at its upper end in an enlarged sleeve portion 50 in which is seated a compression spring 51 loosely surrounding the guide rod 32 and movable with the float upwardly through an opening 52 in a trip valve arm 53 and against a flange or collar 54 fixed to the rod 32 in such manner that the rod will be raised upwardly to open the drain 16 and project its nose portion 35 into blocking position in the duct portion 43, the latching spring means 37 holding the rod in raised position as aforesaid while the water escapes through the drain and the float 31 descends on the guide rod.

In order to spill the air from the tank and effect a sudden upward movement of the float 31 as a result of the reduced pressure, there is provided a trip valve 55 operated by the arm 53 which is pivoted as at 56 on the inner side of the cover 11, the arm 53 being curved such that as the float 31 rises to engage the spring 51 with the rod lifting the collar 54, the arm 53 will be quickly raised to open the valve 55 and spill the compressed air remaining in the tank through a circuitous exhaust line 57 threaded into a nipple 58 in the top of the tank. Meanwhile, the column of water will descend until the float 31 reaches its normally lowered position and engages the plug portion 34 to retract or lower the guide rod 32 and close the discharge opening 16.

Attention is called to the fact that the arrangement of the spring 51 for establishing a yielding operative connection between the float and the means 54 on the upper end of the guide rod, together with the disposition of the trip valve lever 53, is especially designed to assure that the float will be sufficiently submerged in order to cause its sudden upward movement responsive to spilling the air from the tank.

Thus, it will appear that we have provided a novel and inexpensive compression device in which a fluid such as water is injected into a closed tank and provided with an air induction mechanism by means of which a certain quantity of air is led into the tank along with the fluid or water and compressed as the column of water rises within the tank. When a predetermined quantity of water or fluid has entered the tank,

a float mechanism automatically opens a drain valve and permits the water to escape rapidly until the tank is substantially drained, whereupon the drain valve automatically closes and the tank again fills in the manner described. And while we have described a particular use for the mechanism as well as certain specific details of construction thereof, it is expressly to be understood that the invention is not limited to any particular application, nor to any specific form of construction except as may be provided hereinafter in the appended claims.

Having thus described our invention, what we claim as new and desire to protect by Letters Patent is:

1. A compressor including a closed tank, means providing a flow of water into said tank and arranged to induct air into the tank by the flow of water, a water discharge valve arranged in the tank, an air exhaust valve in the tank, a vertically extending guide rod operatively connected with said water discharge valve and movable in a vertical direction to open said valve, a float guided for vertical movement by said rod and having means operatively engaging an upper end portion of said rod to lift the latter and open said water discharge valve when the water reaches a predetermined level in said tank, and resilient means arranged at the upper end of said rod and releasably holding the rod in raised valve opening position, said float being operable to close said discharge valve when a determined amount of water has escaped through said water discharge valve.

2. An air compressor including a closed tank having a water discharge valve in its lower region and an air escape valve in its upper region, a vertical guide rod operatively connected with said water discharge valve and having guided support at its upper end for vertical movement to open said valve, yieldable means at the upper end of said rod and constructed to releasably grip the same and hold the rod in raised position, a float having vertically guided sliding movement on said rod, spring means arranged at the upper end of said float and engageable with means at the upper end of said rod to lift the latter when the float is raised to a predetermined position to open said discharge valve, and a combination water and air injection device connected to a supply of water under pressure, and adapted to draw air into the tank, whereby the level of water in said tank may be raised to compress air therein for escape through said exhaust valve, said discharge valve being opened when said float is raised to said predetermined position by the water.

3. An air compressor including a closed tank having a discharge opening in its lower end and an exhaust valve at its upper end, a valve plug movable vertically into and out of said discharge opening to open and close the latter, a vertically extending guide rod attached to said plug and having guided movement at its upper end in said exhaust valve member, yieldable means having sliding engagement with said upper end portion of the rod and constructed to hold the latter in releasably raised position when the rod is moved a predetermined distance upwardly to raise said plug and open said discharge opening, a float slidable on said rod and normally disposed in a lowered position thereon to lower said plug and close said discharge opening, spring means at the upper end of said float and movable on said rod with said float for engagement

with means on the upper end of said rod to raise the latter said predetermined distance when said float is raised to a particular level by water within the tank, and means attached 5 to a source of water under pressure for injecting water and air into said tank, the rising level of water in said tank compressing said air for escape through said exhaust valve member, said float being raised to said particular level 10 by the injected water to raise said plug and release the water, said float descending to lower said plug preparatory to a repetition of the aforesaid operation.

4. A device of the class described including a 15 closed tank having a water drain in its lower region and an air exhaust opening in its upper region, means for introducing water and air into the tank in a manner to compress said air as the volume of water increases, plug means 20 normally closing said water drain and movable vertically to open the same, a guide rod operatively connected with said plug means, an exhaust valve attachment in said air exhaust opening, yieldable means arranged in said exhaust 25 attachment and guidingly embracing an upper end portion of said guide rod and adapted to hold said rod releasably in raised position when the rod is moved upwardly a determined distance, check valve means in said exhaust valve 30 attachment permitting the escape of air under pressure from said tank for utilization purposes, a float having vertically guided movement on said rod, said float being movable upwardly to a predetermined level by water rising in said 35 tank and having resilient means operatively engageable with means near the upper end of said rod for effecting upward movement of said rod said determined distance by movement of said float to said predetermined level whereby said 40 plug may be raised to permit draining water from said tank, said float being adapted to descend into an initial position within said tank when water is drained therefrom to lower said plug and close said drain.

5. The device of claim 4 further characterized 45 by the provision of a normally closed air trip valve in said tank and having an operating member operably engaged by said float as the latter approaches said predetermined level, whereby the compressed air within the tank may be quickly relieved to effect a sudden upward movement of the float to said predetermined level to raise the guide rod as aforesaid.

6. A fluid-operated compressor including a 55 closed tank, water injection means for introducing water under pressure within said tank, air induction means cooperable with said water injection means for inducing air within the tank by the flow of water therein, a normally closed 60 water discharge valve in the tank, means providing an air discharge passage from said tank, a rod member having a particular end portion guidedly received in said discharge passage and having operative engagement with said water discharge valve to open the latter, a float within 65 said tank and having guided movement on said rod member, spring means movable by said float into engagement with a member on said rod near said particular end to raise the rod and open said 70 water discharge valve when the float is raised to a determined level by water in the tank, means releasably holding said rod in raised position, said float being adapted to descend into an initial position to close said discharge valve when the 75 water level recedes.

7. A fluid-operated compressor including a closed tank, water injection means for introducing water under pressure within said tank, air induction means cooperable with said water injection means for inducing air within the tank by the flow of water therein, a normally closed 5 water discharge valve in the tank, means providing a valve air discharge passage leading from said tank, said passage having a seat portion, a rod member having a particular end portion guidedly received in said discharge passage and having a portion of said particular end constructed to fit in the aforesaid seat portion in the air passage to close off the latter when said rod is raised to open said discharge valve, said rod further 10 having operative connection with said water discharge valve to open the latter, a float within said tank and having guided movement on said rod member, spring means movable by said float into engagement with a member on said rod near 15 said particular end to raise the rod and open said water discharge valve when the float is raised to a determined level by water in the tank, means releasably holding said rod in raised position, said float being adapted to descend into an initial 20 position to close said discharge valve when the water level recedes.

8. A fluid-operated compressor including a closed tank, water injection means for introducing water under pressure within said tank, air 30 induction means cooperable with said water injection means for inducing air within the tank by the flow of water therein, a normally closed water discharge valve in the tank, means providing an air discharge passage from said tank, 35 a rod member having a particular end portion guidedly received in said discharge passage and having operative engagement with said water discharge valve to open the latter, a float within said tank and having guided movement on said rod member, spring means movable by said float into engagement with a member on said rod near 40 said particular end to raise the rod and open said water discharge valve when the float is raised to a determined level by water in the tank, an annular spring member yieldingly embracing said 45 particular end portion of the rod adjacent said discharge passage and engaging in a groove formation in said rod to hold the latter releasably in raised position when the rod is raised to open 50 the water discharge valve, said float being adapted to descend into an initial position to close said discharge valve when the water level recedes.

9. A fluid-operated compressor including a closed tank having a fluid discharge opening in 55 its lower region and an air exhaust opening in its upper region substantially opposite the aforesaid discharge opening, a stop plug normally closing said fluid discharge opening and having connected thereto one end of a guide rod movable 60 vertically into a determined position to open said fluid discharge opening, exhaust valve means arranged in said air exhaust opening and providing an air discharge passage in which the opposite end portion of said guide rod is guidedly received, releasable means for holding said guide rod in said determined position, said means including a toroidal spring member embracing said opposite end portion of the guide rod, the latter having a groove in which said toroidal spring 65 member is moved to said determined position, a float having guided movement on said rod and having a coil spring movable therewith on the rod, a normally closed air relief valve in said tank 70 and having an operating lever provided with an 75

opening surrounding said rod near its upper end and through which said spring on the float may pass for engagement with a member on said rod near said opposite end thereof, such that said 5 float may engage and operate said operating lever of the relief valve to actuate the latter as the float approaches a predetermined level and at substantially the same time establish operative connection with said rod for movement of the 10 latter into said determined position when the air is relieved, and a combination liquid and air injection device connected with said tank for introducing liquid and air within the tank.

10. The device of claim 9 in which said exhaust valve means includes a chambered portion having a normally open fluid-operated valve in communication with an exhaust outlet and adapted to close said exhaust outlet when fluid other than air enters said chamber.

20. 11. The device of claim 9 in which said exhaust valve means includes a tapered air discharge passage into which said opposite end portion of the guide rod fits when the rod is moved into said determined position to close off 25 the movement of air from said tank through said discharge passage.

12. In an air compressor including a closed tank having a water drain valve, an air exhaust valve, an air relief valve, and means for introducing water and air to said tank, the air being compressed by the rising body of water, automatic valve control means including a water drain valve operating member arranged for vertical reciprocation to open and close said drain 35 valve, a float having guided movement on said operating member and operable in a lowered condition to close said drain valve, said float having a spring member engaging an upper part of said operating member when water rising in the tank 40 lifts the float to a particular level, an operating arm for said relief valve and arranged to be operated by said float to open said relief valve substantially at the time when said spring member engages the drain operating member as aforesaid, said float moving suddenly to open said 45 drain valve through the agency of said spring member when said relief valve is operated.

13. Automatic valve control means as set forth in claim 12 and further characterized by the fact that said drain valve operating member is also constructed for cooperation with said air exhaust valve to close off an air exhaust passage through 50

the latter when said water drain valve is opened.

14. Valve mechanism for use with hydraulic air compressors of the type including a closed tank with a hydro-air injector, a water drain valve, and air exhaust and relief valves, said 5 mechanism comprising a float having guided movement on an operating member for said water drain valve and arranged to be lifted to a predetermined level by water rising in the tank to effect an operative connection with said operating member to move the latter for the purpose of opening said drain valve upon continued rising movement of the float, resilient means for operably connecting said float with said operating member, and relief-valve operating means 15 arranged in said tank for operation by said float substantially at or after the time when said float establishes operative connection with said drain valve operating member through the resilient means as aforesaid.

15. In a device of the class described, an inclosed tank, means for injecting air and water into said tank to effect compression of said air by the increasing volume of water in the tank, a normally closed water drain valve for said tank, 25 a valved air exhaust connection for said tank, and float mechanism including a guide rod having operative connection with said drain valve, float means arranged for guided movement relative to said rod and movable in a direction from 30 one end of the rod toward the other as said volume of water increases and decreases, said float mechanism moving said rod to open said drain valve when there is a predetermined volume of water in said tank, yieldable means embracing an end of said rod and operable to hold the latter in valve opening position when said rod is moved by said float means to open said drain valve, said float means moving relative to said rod to close said drain valve when a determined 40 quantity of water has been drained from the tank, an air relief valve in said tank and including an operating member arranged in the path of movement of said float means for actuation by the latter in advance of the opening thereby of 45 said drain valve whereby to effect a sudden relief of the air pressure within the tank and a subsequent positive opening operation of said drain valve.
